UNITED STATES PATENT OFFICE.

MICHAEL W. FAHERTY, OF LOS ANGELES, CALIFORNIA.

RAM.

Application filed September 21, 1925. Serial No. 57,771.

In a ram and cylinder combination as, for example, in a cotton-seed press, the cylinder is provided near its outer end with an annular groove for receiving a packing crimp. 5 This crimp must be renewed from time to time and no satisfactory method has been devised heretofore for effecting this renewal without the cost of considerable time and labor. The usual practice is to remove the 10 press box and the ram cap and to withdraw the ram completely from the cylinder. This frequently requires several hours work of three or four men. According to one expedient by which the removal of the entire ram 15 is avoided, the ram is formed in two parts, the top part being detachable from the main bottom part for exposing the packing crimp. The joint between the two parts can, however, never be made entirely smooth and the 20 consequent greater wear on the crimp necessitates a more frequent renewal thereof.

According to the present invention I provide means for preventing the ram from passing below the crimp in normal action 25 but permitting the ram to fall below the crimp when it is desired to expose the packing. Specifically I provide a stop member in the lower part of the cylinder adapted to abut the ram for limiting its inward travel 30 or to enter in a recess in the bottom of the ram upon a rotation of the latter so that the ram may pass inwardly beyond the crimp. I also provide an accessory implement for aiding in the manipulation of the ram. 35

I shall describe my invention with particular reference to the accompanying drawings, in which—

Fig. 1 is a top plan view of a ram cylinder and cap, the press columns being shown 40 in section;

Fig. 2 is a section on the line 2—2 of Fig. 1;

Fig. 3 is a section on the line 3—3 of Fig. 2;

Fig. 4 shows a portion of a view according to Fig. 2 (the parts being in different relative position) and in cross section an accessory implement; and

Fig. 5 shows the implement in top plan view.

Referring to the drawings, 10 is a hydraulic cylinder, 11 a ram working therein, while 12 is a ram cap supported on the outer end of the ram and having dowel pins 13 adapted to engage in corresponding recesses 14 in the ram. The ram cap is prevented from

turning by the columns 15 and the ram is prevented from turning relative to the cap by means of the dowel pins above mentioned. In the bottom of the cylinder is an abutment 16 of polygonal horizontal cross-section. This abutment is preferably integral with the cylinder. The end wall 17 of the ram is provided with a recess 18 having the same shape as the abutment 16, although being slightly larger. During the normal operation of the ram the recess 18 is at right angles to the abutment 16, as may be most clearly seen from Fig. 3. Under such conditions the projection does not enter the 70 recess and the inward travel of the ram is thus limited by the contact of wall 17 with the abutment so that the upper end of the ram is prevented from passing below the crimp 19.

If, however, it is desired to change the crimp, the operating medium is introduced into the cylinder and the ram elevated. The ram cap and press boxes are securely blocked in elevated position, whereupon the 80 ram is allowed to descend and disengage from them. The annulus 20 (Figs. 4 and 5) is provided with handles 21 having shanks 22 projecting through the annulus and adapted to engage in holes 14 of the ram. 85 The annulus is placed in position on the upper face of the ram and the latter is rotated thereby through an angle of 90 degrees. This rotation brings the abutment 16 and recess 18 into register, and upon exhausting the pressure fluid from the cylinder the ram is permitted to descend to the position shown in dotted lines in Fig. 2, thereby bringing its upper face beneath the crimp 19 so that the latter is exposed upon 95 removing the annulus 20. The new crimp is now inserted and the annulus readjusted in operative position, as shown in Fig. 4, so as to hold the crimp in place. The pressure fluid is now admitted to the cylinder and the ram lifted and turned by means of the handles 21 back to its original position, in which the instrumentalities 16 and 18 again assume the position shown in Figs. 2 and 3.

Having thus described my invention, I claim:

1. In combination, a cylinder having an end wall element, a ram element in said cylinder, and an abutment on one of said elements intermediate the two elements, said abutment being normally adapted to abut

the other of said elements on the inward stroke of said ram element, said other element having a recess, said elements being relatively adjustable for permitting said 5 abutment to enter said recess.

2. In combination, a cylinder having an end wall element, a ram element in said cylinder, and an abutment on one of said elements intermediate the two elements, the 10 other of said elements having a recess, said abutment being normally in non-registering position relative to said recess but being adapted to register with said recess upon a rotation of said ram element relative to said 15 cylinder, for the purpose described.

3. In combination, a cylinder having an end wall element, a ram in said cylinder, an axial abutment of polygonal cross-section on one of said elements intermediate the two 20 elements, the other of said elements having

an axial recess of cross-section similar to said abutment, said abutment and recess being normally in non-registering position but being adapted to register with each other upon a rotation of said ram element relative to 25 said cylinder, for the purpose described.

4. In combination, a cylinder having an end wall, a ram in said cylinder, and an axial abutment of polygonal cross-section on said end wall within the cylinder, said ram 20 having a recess of cross-section similar to said abutment, said abutment and recess being normally in non-registering position but being adapted to register with each other upon a rotation of said ram relative to said 35 cylinder, for the purpose described.

The foregoing specification signed at Los Angeles, California, this 20th day of August, 1925.

MICHAEL W. FAHERTY.
